UNITED STATES PATENT OFFICE.

JOSEPH S. SHEPHERD, OF VINTON, VIRGINIA.

MAIL-BAG CATCHER.

No. 922,203.

Specification of Letters Patent. Patented May 18, 1909.

Application filed March 11, 1909. Serial No. 482,730.

To all whom it may concern:

Be it known that I, JOSEPH S. SHEPHERD, a citizen of the United States of America, and a resident of Vinton, county of Roanoke, 5 State of Virginia, have invented certain new and useful Improvements in Mail - Bag Catchers, of which the following is a full and clear specification, reference being had to the accompanying drawings, in which—

10 Figure 1 is a plan view showing my device ready to receive a mail-pouch; Fig. 2 is a plan view of the casing containing the ratchet mechanism, the top of the casing being removed; Fig. 3 is a transverse section 15 on the line 3—3 of Fig. 2; and, Fig. 4 is a detail perspective of the locking or holding fork.

The object of this invention is to provide a simple attachment for the ordinary pouch- 20 receiving hook now employed on mail-cars which when operatively connected to the hook will automatically lock the pouch in the crook of the hook and thus prevent the pouch rebounding out of the hook and falling 25 to the track-bed, as more fully herein-after set forth.

In the drawings, *a* designates the usual 30 rotary horizontal rod extending across the doorway of the car and provided with the operating handle *b* and the usual receiving hook *c*. The casing *d* is detachably attached to the rod *a* by means of a suitable clamp loop *e* and by means of a pair of hooks *f* adapted to engage an adjacent portion of 35 the hook *c*, whereby the casing is supported in a horizontal position in front of the mouth of the hook *c*.

Working longitudinally through the casing *d* is a rack-bar *g* and pivotally attached to 40 the outer end thereof by a vertical pivot *h* is a rearwardly extending bar *i* whose rear end is bifurcated to straddle the shank or neck portion of the hook *c*, this bifurcation being for the purpose of guiding the bar in its 45 swinging movements. Engaging the rack-bar is a cog-gear *j* attached to a vertical shaft *k* journaled in the casing and connected to a clock-spring *l* which normally tends to rotate the shaft *k* and thus project the rack- 50 bar. On the shaft *k* are two ratchet wheels *m* and *n* whose teeth are faced in opposite directions. A pawl *m'* is held normally in engagement with the wheel *m* and a pawl *n'* is held normally in engagement with the 55 wheel *n*. By means of a cam *m*² the pawl *m'* may be held out of engagement and by

means of a cam *n*² the pawl *n'* may likewise be locked away from its companion ratchet wheel. The cam *m*² is provided with an operating thumb-piece *m*³ and the cam *n*² is 60 provided with a similar thumb-piece *n*³. The shaft *k* has one of its ends squared at *o* for the application of a key or wrench to wind up the spring *l* and draw back the 65 rack-bar.

A trip-arm *p* is pivoted at *p'* and extended outwardly beyond the casing across the mouth of the hook *c*, and the inner extremity of this arm is formed into a pawl *p*² which is adapted to engage the ratchet wheel *n*. The 70 position of the device when set ready for operation is shown in full lines in Figs. 1 and 2. In this position the trip-arm *p* extends across the mouth of the hook *c* and its pawl *p*² engages ratchet wheel *n* and thus locks the rack 75 bar in its innermost position, in which position the locking or clamping arm *i* will lie as shown in Fig. 1. In this position the pawl *m'* is left free to rest against its wheel *m* while the pawl *n'* is held away from its wheel *n*. 80 When the incoming bag strikes arm *p* and throws it back to the position shown in dotted lines in Fig. 1, pawl *p* is disengaged from ratchet wheel *n* and thus releases the spring 85 actuated shaft *k*. This will permit the shaft *k* to quickly turn and project the rack-bar, thereby throwing the locking bar *i* across the mouth of the hook *c* which action will lock or 90 clamp the pouch in the crook of the hook.

To re-set the apparatus the pawl *n'* is released and the pawl *m'* locked out of action. The rack-bar is then drawn back to its original position in which position it will be locked by the pawl *n'*. When thus drawn back the trip arm is swung around across the mouth of 95 the hook, in which position its pawl *p*² will be again in engagement with ratchet wheel *n*. The pawl *n'* is then locked out of action and the pawl *m'* is released. The apparatus is then ready for another operation.

It will be observed that the rack-bar may be withdrawn by taking hold of the handle *g'* at its inner end or by simply rotating shaft *k* by means of the crank-wrench applied to the angular part *o*.

Having thus fully described my invention, what I claim as new, and desire to secure by Letters Patent, is:—

1. In combination with a pouch-receiving hook, a frame adapted for attachment thereto, a reciprocating spring-projected rack-bar therein carrying means for closing the mouth 110

of the hook when the rack-bar is projected, and a tripping-pawl having an extension lying in the path of the incoming pouch.

2. In combination with a pouch-receiving hook; a frame or support detachably connected thereto; a rack-bar slidably mounted in said frame; means for projecting said rack-bar embodying a pinion, a shaft, a spring, a double pawl and ratchet mechanism, and a 10 tripping pawl device.

3. The combination with a pouch-receiving hook, of a frame thereon, a sliding rack-bar in said frame and spring means for pro-

jecting it, a pivoted plate on the outer end of the rack-bar adapted when the rack-bar is 15 projected to swing across the mouth of the hook, a ratchet device for controlling the movements of the rack-bar, and a trip device.

In testimony whereof I hereunto affix my 20 signature in the presence of two witnesses this 9th day of March 1909.

JOSEPH S. SHEPHERD.
